UNITED STATES PATENT OFFICE.

SAMUEL C. HANNA, OF SHELBY, OHIO, ASSIGNOR TO FRANK BENJAMIN ZIEG, OF FREDERICKTOWN, OHIO.

REVERSIBLE IRRIGATING AND DITCHING MACHINE.

1,076,632.

Specification of Letters Patent. Patented Oct. 21, 1913.

Application filed November 15, 1909. Serial No. 528,102.

To all whom it may concern:

Be it known that I, SAMUEL C. HANNA, a citizen of the United States, residing at Shelby, in the county of Richland and State of Ohio, have invented certain new and useful Improvements in Reversible Irrigating and Ditching Machines, of which the following is a specification.

My invention relates to an improvement 10 in reversible irrigating and ditching machines, and it is an object to provide a rigid means of attachment for adjusting the scraper to either throw the dirt to the right or left.

15 A further object is to provide means to effectually prevent the end of the machine carrying the scraper from slipping or skidding due to the resistance of the dirt being scraped and moved by the scraper.

20 Another object is to provide means for keeping the rear wheels continually working in the direction from which the machine is inclined to slip, thus continually resisting the natural tendency of the machine to be 25 pushed aside by the dirt in front of the scraper.

Still another object is to provide means for affording freedom of axial movement between the forward truck and the scraper, 30 thus preventing the front truck from overturning.

With these several objects in view, my invention consists in a reach, a forward truck with which the reach has a swivel connection, a scraper, means for reversing the latter, and locking it in position with respect to the reach, and means at the rear for resisting the tendency of the machine to slip or slide away from the dirt being 35 scraped and moved.

My invention further consists in certain novel features of construction and combinations of parts which will be hereinafter described and pointed out in the claims.

40 In the accompanying drawings:—Figure 1 is a view in side elevation, Fig. 2 is a plan view showing the parts in their normal position, Fig. 3 is a plan view showing the scraper and rear wheels in the position assumed when throwing the dirt to one side, Fig. 4 is an enlarged, longitudinal, vertical section through the mechanism for locking the scraper, Fig. 5 is an enlarged detail 45 partly in section showing the guiding blade and means for adjusting the latter, and Fig.

6 is an enlarged detail, partly in section, showing one of the rear wheels with the lever for raising and lowering the scraper.

The reach preferably consists of two parallel bars 1, 1, spaced apart at the rear by 50 casting 2, to which the rear end of the parallel bars are fitted as at 3, 3, at or near the center by a block 4 to which the parallel bars are secured by bolts, or rivets 5, 5, and the forward ends of the parallel bars have 55 secured therein the socket plate 6 which clamps between its sections the ball 7 which projects rearwardly from the sleeve 8, in which the shank 9 of the forward truck 10 is pivoted, thus providing a connection where- 60 by the forward truck 10 may not only be turned to the right or left, but also whereby it may swivel axially with respect to the reach or vice versa. An arm 11 extends up- 65 wardly from the level of the axle, and is 70 provided with a clevis 12 to which draft is applied, and the link 13 extends from the upper end of this arm to the upper end of the shank 9, as shown in Figs. 1, 2, and 75 3. The scraper 14 is secured at its center 20 to a bracket 15, and this bracket is pivotally connected to the rear end of the casting 2, by means of a stud 16. A bow 17 approxi- 25 mately semi-circular in form, as shown in Figs. 2 and 3, is secured at its ends to the 30 grader at points equidistant from its center 35 of oscillation. This bow 17 is provided with orifices 18, 18, throughout the greater 40 part of its length, and it passes freely 45 through the space 19 between the upstand- 50 ing lugs 20, 20, of the block 4, at which point 55 a sliding bolt 21 operating through orifices 60 22, 22, is arranged to enter the holes 18, in 65 registry therewith, whereby to lock the 70 scraper in the desired position. A foot lever 75 80 85 90 95 100

is fulcrumed at 24, within easy reach of the operator's foot, when occupying the driver's seat 25; and a link 26 connects the forward end of this foot lever with the locking bolt 21. A spring 27 normally holds 105 this foot lever in an elevated position with the bolt 21 thrown forward, as shown in Fig. 4, or resting against the solid portion of the bow, in position to pass into one of the holes 18, as soon as the latter is turned 110 in position therefor. To remove the bolt 21, therefore, pressure is applied upon the foot lever. In this way, a very simple means is provided for locking the scraper at the desired angle, the change in angle 115

being effected by swinging the reach to the right or left, accordingly as the dirt is to be thrown to the left or right.

As a means for raising and lowering the scraper, and regulating its depth of cut, toother segments 28, 28, are hinged vertically to the rear of the scraper 14 at or near the outer ends thereof. A hand lever 29 provided with the usual latch 30 is pivotally connected as at 31, with each of said segments, and each of these levers carries a stem 32, and a wheel 33 is journaled to the rear end of each of said stems 32. It is obvious that the swinging of the lever forward or rearward, lowers or raises the scraper, and determines the depth of cut. To assist in resisting the tendency of the wheels 33, 33, to slide laterally, these wheels are provided with circumferential flanges 34, which cut into the ground and counteract the tendency of the wheels to slide. As a further means of preventing sliding and skidding, the runner 35 is provided. This is pivoted at its forward end as at 36 to the arm 37, and its rear end is raised or lowered through the medium of a hand lever 38, fulcrumed on the rear of the scraper 14, and the link 39 extending to the runner 35. The runner 35 is provided with several holes 40, 40; one of which is to receive pin or bolt 41, according to the vertical adjustment of the runner. The arm 37 which supports the runner is pivotally connected at its forward end to the rear of the scraper as at 42, and from the rear end of this arm, braces 43, 43, extend in opposite directions to a connecting bar 48, which extends across from one segment 28 to the other. The connecting bar 48 which may be used or not has a stud 49 which extends into a slot 50 in the rear end of casing 2, to afford additional support when the scraper is in a position at right-angles to the line of draft, as shown in Fig. 2 the slot extending longitudinally of the casting, and permitting the stud forward and rearward play therein. Two additional rods 51, 51, extend from the segment 28 to the rear end of the casting, where the latter is provided with a series of holes 53, 53, to which the inner ends of the rods 51, 51, are adjustably connected by bolts or similar means 54, 54. The purpose of the bar 48, and the rods 51, 51, is to shift and regulate the direction of the rear wheels 34, 34, and the runner 35, they being turned simultaneously with the adjustment of the scraper as illustrated in Fig. 3, into a position of resistance to the tendency of the scraper to yield to and slide away from the dirt being moved thereby. In other words, the two wheels and runner coöperate to hold the scraper steadfastly to its work. When it is desired to shift the wheels 34—34, the stud 49 is removed from slot 50, and the bar 48 may also be removed, as shown in Fig. 3.

It is understood that the direction of the wheels and runner are changed by shifting the inner ends of the rods 51, 51, to different holes 53 in the casting 2, as in this way the circle is shortened or lengthened, and the angle of the wheels is correspondingly varied.

It is evident that more or less slight changes might be resorted to in the form and arrangement of the several parts described without departing from the spirit and scope of my invention, and hence I do not wish to limit myself to the exact construction herein set forth, but:—

Having fully described my invention, what I claim as new and desire to secure by Letters Patent, is:—

1. The combination with a reach, a scraper hinged thereto, and wheels carried by the scraper, of a runner carried by the scraper and connected with the said wheels, and means connecting the wheels with the rear end of the reach, whereby the position of the wheels and runner varies with the position of the reach and scraper with respect to each other.

2. The combination with a reach and a scraper hinged thereto, of a runner hinged in rear of the scraper, and means for shifting the free end of the runner laterally, and means for adjusting the free end of the runner vertically.

3. The combination with a reach and scraper hinged thereto, and wheels carried by the scraper, of a runner hinged to the scraper and having its free end connected with the wheels, a connecting bar extending from one wheel to the other and loosely connected with the reach.

4. The combination with a reach and scraper hinged thereto, the extreme rear end of the reach having a slot which extends lengthwise thereof, of segments hinged to the scraper, wheels carried by the segments, a runner hinged to the scraper, a connecting bar extending from segment to segment, braces extending from the rear end of the runner to the connecting bar, and a stud carried by the connecting bar and working in the slot in the rear end of the reach.

5. The combination with a reach and a scraper hinged thereto, of segments hinged to the scraper, levers pivoted to the segments and carrying wheels, and rods pivotally connected to the segments and adjustably connected to the reach, a connecting bar extending across from segment to segment, and a runner having hinged connection at its forward end with the scraper, and its rear end connected with said connecting bar.

6. The combination with a reach and a scraper pivotally connected therewith, of a bar extending rearwardly from the scraper, braces therefor, a runner pivotally con-

- nected at one end to the said bar, and adjustably connected to the bar at the other end, and means for raising and lowering the free end.
- 5 7. The combination with a reach, a scraper pivotally connected therewith, a forward truck at the forward end of the reach, and rear wheels rearward of the scraper, of a bar hinged at its forward end to the
- 10 rear of the scraper, a connecting bar extending from one rear wheel to the other, braces extending from the first-mentioned bar to the connecting bar, and a runner pivotally connected at its forward end to the forward
- 15 end of said first-mentioned bar and adjustably connected at its rear end to the rear end of said bar, and means for raising and lowering said rear end of the runner.
8. The combination with a scraper, of wheels and a runner pivotally connected to the scraper, means connecting the wheels and runner together, and means for moving the wheels and runner at an angle from the line of draft.
- In testimony whereof I affix my signature, in the presence of two witnesses.
- SAMUEL C. HANNA.
